CLAIM

The ornamental design for a pet bed, as shown and described.

DESCRIPTION

FIG. 1 is a top front perspective view of a pet bed showing my new design;
 FIG. 2 is a bottom rear perspective view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view thereof; and,

FIG. 8 is a back elevational view thereof.

The broken line showing the base in FIGS. 1-8 is included for the purpose of illustrating environmental structure and forms no part of the claimed design.
